UNITED STATES PATENT OFFICE

FRANK G. BROTH, OF KOHLER, WISCONSIN, ASSIGNOR TO KOHLER COMPANY, OF KOHLER, WISCONSIN, A CORPORATION OF WISCONSIN

SWINGING COVER FOR DISHWASHERS AND THE LIKE

Application filed November 18, 1925. Serial No. 69,836.

This invention has for its object to provide a swinging cover for receptacles such as the dish-containers of dishwashers and the like, which cover will form a sealing closure 5 confining the water within the container and the like, though it is thrown in forceful jets or violently agitated.

Another object of the invention is to provide such a cover which will produce a cushioning effect on closing, preventing injury thereto even though it may be made of glass and also preventing injury to the container though it may have a vitreous enamel surface.

15 Another object of the invention is to provide such a cover which will constitute a glass drain board for a sink combined in the same fixture with the dishwasher.

With the above and other objects in view 20 the invention consists in a swinging cover for dishwashers and the like as herein claimed and all equivalents.

Referring to the accompanying drawings 25 in which like characters of reference indicate similar parts in different views,

Fig. 1 is a plan view of a combined dishwasher and sink provided with the swinging cover of this invention;

Fig. 2 is a sectional view thereof showing 30 the cover in elevation in full lines in its closed position and in dotted lines in its open position;

Fig. 3 is a front view of the cover in its open position;

Fig. 4 is an enlarged sectional view through 35 the cover at one of the hinges, and

Fig. 5 is a detail sectional view showing a modification.

In these drawings, 10 indicates the receptacle or container of a dishwasher, which 40 is preferably of enameled iron ware and may be formed integral with a sink 11, the cover for the container to constitute the drain board for the sink.

45 The cover 12 for the dishwasher container or receptacle is preferably of glass with or without a woven wire re-enforcement embedded therein, though it may be of metal or of other suitable material and is pivotally mounted to lie either in an approximately

horizontal closed position or in a vertical open position as by means of hinge members 13 bolted to the back of the dishwasher. The connections of the hinges with the cover and the dishwasher back are made with intervening gaskets 14 of rubber or other cushioning material that will prevent injury to the glass cover or the vitreous enamel surface. The hinges are preferably of the spring type to more or less counterbalance the weight 55 of the cover.

Entirely surrounding the cover is an inclined rubber flap 15 just beneath the edge of the cover and spaced therefrom to engage the inclined surface of the rim of the dishwasher and form a yielding sealing cushion between said rim and the cover.

This yielding rubber flap 15 is preferably formed of a rubber strip with a beveled or tapered inner edge confined between the bottom surface of the cover and an inclined metal frame 16, where it is clamped by means of screws 17 threaded into headed metal posts 18 let through openings in the cover, as clearly shown in Fig. 4. Where the hinges are 60 located screws 19 are substituted for the screws 17 and they thread into the hinge members and carry metal plates 20 with one edge turned over to engage the edge of the metal frame 16, the other edge engaging a 65 rubber filler strip 21. The inner surfaces of both the hinge member and the clamp plate 20 are concave so that the rubber engaged thereby will be compressed at the edges and will not be spread and protruded by the 70 clamping action of screws 19.

75 The yielding rubber flap around the edge of the cover with its free edge spaced from the bottom of the cover forms a flexible lip that will not only cushion the closing movements of the cover by its resiliency, but by forming an air-tight sealing connection with the rim of the dishwasher so as to produce a

80 dashpot effect causing the air within the receptacle of the dishwasher to become compressed and act as a cushion to stop the movement of the cover quietly and without inflicting a blow thereon that would be likely 85 to break the glass. This effect is the same

90 whether the springs are counterbalanced or 95

100

not, for the counterbalancing by the springs is not such as to overcome the weight of the cover in its horizontal position but merely to make it easier to move the cover from one position to another and to reduce the blow struck should the cover be released and allowed to fall.

The air cushioning effect of the rubber flap is effective for producing a silent and harmless stop for the cover when the cover is permitted to fall from any position.

In Fig. 5 is illustrated a modification wherein the rubber flap 15' is of the same thickness and the metal frame 16 is parallel with the cover. The cover 12' in this instance is of metal and provided with a bead 21 on its bottom surface, against which the rubber flap bears to give it the inclination that will cause its edge to be spaced from the edge 20 of the cover.

In addition to the sealing effect of the flexible rubber lip in cushioning the closing of the cover, it effectively prevents the discharge of water under the edge of the cover even 25 when the dishwasher is of the type which depends upon forceful jets of water thrown in all directions. As the rubber lip bears on an outwardly inclined surface of the rim, there is no gutter or trap to hold water but the water is shed back to the bottom of the receptacle without being permitted to collect or escape.

The cover when formed of glass permits the operation of the dishwasher being ob- 35 served and, whether of glass or of metal, forms a drain-board for useful association with the sink. It may be slightly inclined to drain water to the sink.

To protect the glass cover from injury by 40 striking the back of the dishwasher the latter may be provided with a rubber bumper 22, as shown in Figs. 1 and 2.

While the invention is described as the cover for a dishwasher, it will, of course, be understood to be applicable to clothes-washing machines and various other apparatus of a similar nature and the term "dishwasher" as herein used is to be understood as including such other machines and apparatus.

50 What I claim as new and desire to secure by Letters Patent is:

1. A cover for the containers of dishwashers or the like comprising a hinged cover member and a flexible sealing lip surrounding the cover and attached thereto and spaced from the edge of the cover to engage the rim of the container and form an air cushion therewith.

2. In combination with the container of a 60 dishwasher or the like having an inclined rim, a hinged cover therefor having an inclined rubber lip surrounding it and spaced from its edge and contacting with the inclined rim to form an air-tight and water-tight sealing 65 connection therewith.

3. In combination with the receptacle of a dishwasher or the like, a hinged cover therefor, and means for cushioning the fall of the cover comprising a downwardly flaring flexible lip carried by the cover and contacting with the rim of the receptacle in an unbroken line surrounding the receptacle.

4. In combination with the receptacle of a dishwasher or the like having an outwardly inclined surrounding rim, a hinged cover, and 75 a resilient flexible sealing lip secured to the cover around its edge with its outer free edge spaced from the edge of the cover and forming a sealing engagement with the inclined rim of the receptacle.

5. In combination with the receptacle of a dishwasher or the like, a hinged cover therefor, and a rubber strip having a tapered edge secured to the under side of the cover and extending entirely around the cover whereby 85 said rubber strip forms a flexible inclined lip having sealing engagement with the edge of the receptacle.

6. In combination with the receptacle of a dishwasher or the like, a hinged cover 90 therefor formed of a glass plate having openings near its edges, screw posts let into said openings, an inclined rubber lip member having a tapering inner edge, a metal frame engaging the tapering edge of the rubber 95 strip, and screws passed through the metal frame and the tapering edge of the rubber strip and threaded in the screw posts to clamp the rubber strip between said metal frame and the bottom of the cover whereby said rubber strip constitutes an inclined flexible lip for forming a sealing and cushioning engagement with the edge of the receptacle.

7. In combination with the receptacle of a dishwasher or the like having an upstanding back member, a cover comprising a plate of glass, spring hinges for the cover secured to the back member of the receptacle, there being openings in the glass plate near the edge thereof, screw posts let into said openings, a rubber strip, a metal frame engaging the inner edge of the rubber strip, screws passed through the metal frame and threading into the screw posts, said rubber strip forming an inclined flexible lip for engaging 115 the edge of the receptacle, rubber gaskets between the hinge members and the top of the glass plate, clamping plates engaging the edge of the metal frame, rubber gaskets between the clamping plates and the bottom 120 of the glass plate, and screws passing through the clamping plates, the metal frame, the glass plate and threaded in the hinge members.

8. In combination with the receptacle of 125 a dishwasher or the like, a hinged cover therefor provided with a bead on its under surface, and a rubber strip secured to the bottom of the cover and bearing against the bead to be deflected thereby to an inclined 130

position for forming a flexible resilient sealing lip for cushioning engagement with the edge of the receptacle.

9. In combination with the receptacle of a dishwasher or the like, a glass cover therefor, counterbalancing hinges connecting the glass cover with the receptacle, and a flexible flap or hinged cushioning lip surrounding the glass cover and having sealing engagement with the edge of the receptacle.

10. A cover for the receptacle of a dishwasher or the like comprising a hinged cover member and a sealing lip having hinged connection therewith with a free edge spaced from the cover to engage the rim of the receptacle and forming with the receptacle and the cover member an air cushioning means to dampen the fall of the cover.

11. A cover for the container of a dishwasher or the like otherwise sealed receptacle comprising a hinged cover member, and means for cushioning the fall of the cover comprising a flexible lip carried by the cover with a free edge spaced from the cover and movable with respect thereto and contacting with the rim of the receptacle in an unbroken line surrounding the receptacle.

12. A cover for the container of dishwashers or the like comprising a hinged cover member, and means for cushioning the fall of the cover comprising a flexible sealing lip formed by a rubber strip having one edge secured to the cover and the other edge free and spaced from the cover and contacting with the rim of the receptacle in an unbroken line surrounding the receptacle.

13. A cover for the container of dishwashers or the like comprising a hinged cover member and a flexible sealing lip surrounding the cover and attached thereto and spaced from the edge of the cover to engage the rim of the container in an unbroken line surrounding the container.

14. In combination with the receptacle of a dishwasher or the like, a cover therefor, counterbalancing spring hinges connecting the cover with the receptacle, and a flexible lip surrounding the cover and having sealing engagement with the edge of the receptacle.

In testimony whereof I affix my signature.

FRANK G. BROTHZ.
